UNITED STATES PATENT OFFICE

2,474,364

AUTOMATIC WELL POINT

Thomas F. Moore, Morris Plains, N. J.; Edward J. Moore and Mary Moore Dacey, executors of said Thomas F. Moore, deceased, assignors, by mesne assignments, to Moretrench Corporation, Rockaway, N. J., a corporation of New Jersey

Application December 4, 1944, Serial No. 566,409

20. Claims. (Cl. 166—5)

1

The present invention relates to well points for draining or drawing off water and other fluids from the ground.

Wet ground is one of the chief problems and hazards encountered in construction work, and the use of well point systems in recent years has in many cases made possible construction work which otherwise would be totally impossible or impracticable. By the use of such systems, wet ground may be changed into firm, dry soil, work may be started and completed quicker, sheeting or shoring may be wholly or partly eliminated without danger of blow-ins and sand boils, and other "wet costs," such as, rubber boots, planks, runways and much rehandling of material is eliminated. These factors, among others, have fully established the practical advantages of well point systems, and have proved them to be exceptionally valuable where time, labor, and/or materials are of prime consideration, as is the case under present day conditions.

In the usual well point system, a suitable number of well points are jetted or otherwise sunk into the ground to the desired depth, according to the conditions which prevail and the type of construction work to be performed, and these well points are connected to one or more headers, depending on the size of the area to be drained. The headers in turn are connected to a suitable pump, or other suction apparatus, which serves to draw the water from the ground into the well point, and through the headers from which the water may be discharged as waste or otherwise made available for use, such as for mixing concrete, and sometimes even for drinking.

During the soil dewatering operation, the water level may be lowered faster at certain well points than at others in the same system, due to variations in the nature and structure of the soil and other factors. In due time, some of the well points may suck air, unless this is prevented, thereby impairing the suction or vacuum influence of the pump on the other well points of the system, and consequently reducing the capacity and effectiveness of the system as a whole. In order to prevent air from entering the well points, I have developed automatic well points which have all the advantages of the ordinary well points, but which automatically exclude air therefrom, as disclosed, for example, in my prior patents No. 2,164,253, granted June 27, 1939, and No. 2,176,540, granted October 17, 1939.

According to these prior patents above referred to the well points are provided with a float valve

2

located wholly in a float chamber within the body of the well point, and automatically operable by the rise and fall of the liquid level therein to control the admission of ground water into the well point and the exclusion of air, under appropriate conditions.

The present invention has for its primary object the same general objectives of my prior automatic well points as regards the exclusion of air from the well point, but to attain this objective in a more simple and effective manner.

A further object of this invention is to provide an improved float valve mechanism which is characterized by the use of a float or floats having an extremely low or very little buoyancy when submerged in water, in order that substantially the full weight of the float or floats may be utilized to forcibly urge the valve which is connected thereto, to its closed position when the water level at the intake of the well point drops to a level which would tend to allow air to enter the well point.

A still further object of my invention is to provide an improved float valve wherein the valve is so related to its seat that it moves in an upward direction against the bottom of the seat to close the same, and when closed, will be aided, rather than resisted, in its opening movement, by the vacuum influence or suction to which the well point is subjected during the ground draining or dewatering operation.

Another object of the invention is to provide an automatic well point which is so compact in form as to be capable of being readily made in small sizes, such as can be easily handled during the jetting operation, but which has ample capacity, both for jetting and dewatering operations.

Another object is to provide an improved automatic well point which is composed of parts which can be easily and cheaply manufactured and assembled, and which includes a float valve mechanism having the form of a unitary assembly which may be inserted as a unit into the well point body.

Other and further objects and advantages of the invention will be hereinafter described and the novel features thereof defined by the appended claims.

In the drawings:

Figure 1 is a view in vertical section of the upper portion of a well point constructed in accordance with my invention;

Figure 2 is a vertical sectional view of the lower portion of the well point of Figure 1, and being a continuation of Figure 1;

Figures 3 and 4 are vertical sectional views respectively corresponding to Figures 1 and 2, with the plane of the sections at right angles to the latter figures;

Figure 5 is a horizontal sectional view taken on the line 5—5 of Figure 1; and

Figures 6 and 7 are horizontal sectional views taken respectively on the lines 6—6 and 7—7 of Figure 2.

Like reference characters designate corresponding parts in the several figures of the drawings, wherein 1 generally denotes the well point body which is of elongated tubular form and comprises a cylindrical member or pipe 2 having a series of perforations or openings 3 provided therein, and axially spaced lengthwise thereof in one or more rows running vertically of the pipe. As shown in the drawings, the perforations or openings are arranged in two rows at diametrically opposite sides of the pipe, with the perforations of each row equidistantly spaced apart. A coupling 4 is attached to the upper end of the pipe 2 in any suitable manner, as by welding, and the interior of this coupling is threaded, as at 5, so that the well point may be attached in the usual manner to a pipe leading to the jetting and suction equipment of a well point system.

At the lower end of the pipe 2, there is also provided another coupling 6 which is suitably attached thereto, as by welding, and this coupling is likewise interiorly threaded, as at 7, for connection with a jetting tip designated 8. Disposed within the jetting tip is a diaphragm or valve seat 9 having an aperture 10 provided therein, this seat or diaphragm being secured within the tip in any suitable manner, as by welding. Disposed within the jetting tip below the valve seat 9 is a floating ball check 11 which is free to move towards and away from the seat. Downward movement of the ball check 11 is limited by a pin 12 extending transversely through the jetting tip 8 at such distance below the valve seat that, when the ball check rests upon the pin, it will be spaced from the seat 9, thus uncovering the opening 10.

The lower end of the jetting tip 8 is serrated to provide a series of teeth 13 which are utilized to assist in eroding the soil and dislodging the same, by rotary or oscillatory movement imparted to the well point during the jetting operation. These teeth 13 are preferably of a special shape, as more particularly described in my co-pending application, Serial No. 514,686, filed December 17, 1943, now Patent No. 2,388,640.

In order to prevent sand, stones, gravel, and other foreign material from entering the well point during the suction or soil dewatering operation, the well point body is provided with a filter screen designated 14, which extends about the pipe 2 over the intake openings 3. This filter screen is preferably spaced from the pipe 2 by spacing means designated 15, preferably having the form of an asbestos cord spirally wound about the pipe. The details of the filter screen 14 and the spacing means 15, together with their advantages, are fully described in my co-pending application above referred to, and for this reason, will not be repeated herein. It is to be understood, however, that these details are not essential to the present invention, since other forms of filter screens may be employed if desired. According to the arrangement as illustrated in the drawings, the upper end of the filter screen 14 is soldered or otherwise secured to the pipe 2 and to the lower end of the upper coupling 4, as indicated

at 16, and the lower end of the filter screen terminates somewhat above the lower coupling 6, and is soldered or otherwise secured, as at 17, to a ring or collar 18 which is in turn welded, as at 19, to the pipe 2.

Fixed to the upper end of the pipe 2, as by welding, is a partition or diaphragm 20 which extends transversely across the same and is provided with a pair of openings therethrough, the latter openings being designated 21. A second diaphragm or partition 22 is disposed at the bottom of the pipe 2, being preferably positioned between the lower end of the pipe 2 and the upper end of the jetting tip 8, so that, when the jetting tip is screwed into the coupling 6, the diaphragm 22 will be clamped firmly between the jetting tip and the pipe 2, in order to provide a good seal about the diaphragm 22. The diaphragm, together with the bottom end of the pipe 2 and upper end of the jetting tip 8, may be machined or otherwise finished off where they bear against each other.

The lower diaphragm 22 is also provided with a pair of openings 23 which are axially aligned with the openings 21 in the upper diaphragm 20. Extending between the respective pairs of axially aligned openings 21, 22 is a pair of tubes or pipes designated 24. These tubes 24 are preferably secured to the lower diaphragm 22, as by extending the tubes through this diaphragm and soldering or welding the projecting ends of the tubes to the diaphragm, as indicated at 25. The upper ends of the tubes 24 are preferably removably attached to the upper diaphragm 20, and for this purpose, the tubes 24 are projected through the diaphragm 20 to receive couplings 26 which are respectively threaded engaged on the upper threaded ends of the tubes. These couplings 26 are open at their upper ends, and merely serve as fastening means to attach the upper ends of the tubes 24 to the diaphragm 20, acting as hollow nuts which may be screwed down tightly against the diaphragm. As the couplings 26 are screwed up tight against the diaphragm 20, the tubes 24 will be placed under tension. In order to make the connection of the tubes with the upper diaphragm 20 air-tight, the upper ends of the openings 21 through which the tubes extend are preferably beveled or flared outwardly, as indicated at 27, and the lower ends of the couplings 26 are also beveled in a complementary manner so that, on screwing the couplings up tight, they will seal themselves against the upper diaphragm.

It will be seen that the upper diaphragm 20 and the lower diaphragm 22, together define a chamber between each other and within the pipe 2 which is completely isolated from the space within the tubes 24, since the latter tubes are open at their opposite ends respectively above the upper diaphragm 20 and below the lower diaphragm 22. Accordingly, the chamber between these diaphragms, which chamber is designated 28, may be utilized effectively as a float chamber to control the flow of water through the well point when it passes from the ground through the filter screen 14, and then through the openings 3 in the pipe 2, which lead into the chamber 28. The float valve mechanism will now be described in detail, and may be said to comprise a pair of cylindrical float members 29, 29', of metal or other suitable material, to which is attached a valve member 30 coacting with a valve seat 31 provided in the lower diaphragm 22. The construction and arrangement of this float valve mechanism is such that it

offers little or no resistance to closing of the valve 30 when the water level in the vicinity of the well point, and hence in the float chamber 28, falls below a predetermined point, and also so the opening of the valve 30 will be aided by the vacuum influence or suction to which the well point is subjected during the soil dewatering operation, when the water level rises to a point where water may be drawn from the ground through the well point without sucking air. To these ends, the float members 29, 29' are designed to have very little buoyancy when submerged in water, and these members are connected together in a suitable manner, as by means of tie-bolts 31', 31' at their upper and lower ends respectively, in spaced relation to each other, so as to lie on opposite sides of the tubes 24, 24, the latter tubes being suitably spaced from each other as to permit the float members to move freely upwardly and downwardly in the chamber 28 between the upper and lower diaphragms 20, 22. To maintain the float members 29, 29' in spaced relation to each other, spacers 31" are disposed therebetween on the respective tie-bolts 31', 31'. The arrangement of the tubes and float members will be best understood from reference to Figure 5 of the drawings, showing the symmetrical and compactly nested relation of these elements within the chamber 28.

Attached to the lower end of one of the float members, as for example, to the lower end of the float member 29', is a link 32, the upper end of the link being pivotally connected at 33 to an ear or boss 34 on the bottom of the float member 29', and the lower end of the link 32 being pivotally connected at 35 to one end of a lever 36. The lever is in turn supported by a pair of upstanding ears 37, 37 mounted upon a supporting plate 38, which plate is firmly attached to the tubes 24, 24, as best shown in Figure 6 of the drawings, but is loosely fitted in the pipe 2. A pivot pin 39 extends through the ears 37, 37, and the lever 36 which is positioned therebetween and acts as a fulcrum for the lever. The opposite end of the lever 36, beyond the fulcrum, is pivotally connected at 40 to a clevis 41 which is adjustably carried by the upper end of a valve rod 42. The lower end of the valve rod 42 is threaded and screwed into the valve 30 which is preferably hemispherical in shape, the valve being adjustably secured on the end of the valve rod by a jamb nut 43.

It will be observed that the valve 30 is located at the lower side of the diaphragm 22, so that it moves in an upward direction on closing, and in a downward direction on opening. The valve seat 31 is so located in the diaphragm 22 that it lies adjacent to one side of the well point body, and the valve 30 is accordingly positioned in slidable contact with the wall of the jetting tip 8, at the upper end of the latter due to the inclined position of the valve rod 42. This arrangement automatically tends to maintain the valve in proper alignment with its seat, and this, together with the hemispherical shape of the valve, tends to prevent the rush of water past the valve from materially interfering with the correct alignment of the valve on closing against its seat.

As will be seen from the drawings, the lever 36 is located a substantial distance above the lower diaphragm 22, so that sufficient space is afforded below this lever and the supporting plate 38 to accommodate a certain amount of fines which may enter the well point through the filter screen 14 and the intake openings 3 in the pipe 2. These fines would ordinarily tend to collect in the bottom

of the chamber 28 during the jetting operation, at which time the valve 30 is closed by the back pressure of the jetting fluid acting against this valve. However, on completion of the jetting operation and rise of the water level in the chamber 28, the valve 30 will automatically open, allowing the fines to rapidly pass through the port 44 in the diaphragm 22, which is controlled by the valve 30, and into the chamber 45, where they will be drawn up through the tubes 24, 24 responsive to the vacuum influence to which the well point is subjected during the soil dewatering operation. By the provision of the space below the lever 36 and supporting plate 38 to accommodate these fines above referred to, they will not interfere with the automatic operation of the float valve mechanism.

To jet the well point into the ground, the upper end of the well point unit may be attached to a suitable length pipe which is screwed into the upper coupling 4, the pipe being in turn connected by a flexible hose to a pump. Water or other jetting fluid is forced by the pump, at relatively high pressure, downwardly through the well point, where it ultimately emerges at the bottom of the jetting tip 8. In passing through the well point, the jetting water flows downwardly through the tubes 24, 24, from which the water is discharged into the chamber 45 below the lower diaphragm 22 and above the valve seat 9 of the floating ball check valve 11. Due to the pressure of the jetting fluid, the floating ball check valve 11 will be displaced downwardly against the pin 12, so that it occupies the position shown by the dotted lines in Figures 2 and 4, thus allowing the jetting fluid to continue through the jetting tip 8 for action upon the soil at the extreme lower end of the jetting tip. Back waste of the jetting fluid is prevented by the automatic closing of the valve 30 under the influence of the back pressure of the jetting fluid, so that the full pressure of the jetting fluid is maintained at the lower end of the jetting tip for the purpose of displacing the underlying soil, which may be aided by the teeth 13 on the end of the jetting tip. As the soil is loosened and scoured away from beneath the well point, it passes upwardly around the outside of the well point to the surface of the ground, where the washed out material is deposited.

When the well point has been sunk in the ground to the desired depth, the jetting operation is discontinued, and the pipe which is attached to the upper coupling 5 is disconnected from the hose and then connected to a header of the well point system, which header is connected to a vacuum pump or other suction device. On discontinuing the jetting operation, the water remaining in the hole at the bottom of the well point, or the water in the surrounding soil, will float the ball check valve 11 into seating engagement with the valve seat 9, as shown in full lines in Figures 2 and 4 of the drawings, thereby preventing any inflow of material upwardly through the bottom of the well point. The suction action or vacuum influence on the well point, therefore, causes the ground water to be drawn into the well point through the filter screen 14 and the intake openings 3 in the pipe 2 which lead into the float chamber 28. So long as the water level is high enough to prevent air from entering the well point, the float members 29, 29' will assume a position at the upper end of the float chamber which opens the valve 30 through movement imparted to the latter by the

mechanical connections between the float members and this valve. The opening movement of the valve 30 is further aided, or at least materially unimpeded, by the suction or vacuum influence on the well point, having in view that the vacuum influence within the chamber 45 acts upon the bottom of the valve 30, which is arranged to move in a downward direction away from its seat 31. With the valve 30 in its open position, the water from the ground is free to pass from the float chamber 28 into the chamber 45 from which it is withdrawn upwardly through the tubes 24, 24, and thence through the pipe attached to the upper coupling 5 to the header.

Should the water level in the ground become lowered or exhausted to a point where air might be sucked into the well point, the lowering of the water level causes the float members 29, 29' to fall, and this in turn actuates the mechanical connections 32, 36, 41, 42 to close the valve 30, which blocks the port 44 in the diaphragm 22 and prevents any air from entering the chamber 45 where it would otherwise be drawn upwardly through the tubes 24, 24 and into the well point system where it would impair the vacuum influence upon other well points of the system. The closing of the valve 30 is virtually produced by the dead weight of the float members 29, 29', which, as previously indicated, are designed to have very little buoyancy. Thus, the floats require no attention to keep them from absorbing water, as is normally required with ordinary floats which are customarily made of cork or balsa wood for maximum buoyancy, and which also are so bulky as to prohibit their use in well points of relatively small diameter. In the present invention, all that is required of the float members is that they should be just buoyant enough to move easily when the vacuum influence pulls the valve 30 downwardly away from the seat 31. When this happens, the well point is generally full of water and the float members are easily moved, and as the water lowers, the float members exert a continually increasing downward pressure upon the link 32, and thus forcibly pulling the valve rod 42 upwardly through the intermediary of the fulcrum lever 36, and urging the valve 30 to close against the vacuum influence prevailing in the chamber 45.

The simplicity and efficiency of my improved well point will be obvious from the foregoing description, and one of the important advantages of the new well point over those of my prior patents hereinbefore referred to, resides in the elimination of a separate valve member to prevent back waste of the jetting fluid during the jetting operation. The function of this prior separate valve member is performed by the same valve which prohibits the passage of air into the well point system, namely, the valve 30, which, accordingly, has a dual purpose. Moreover, the float valve mechanism, together with the tubes 24, 24 and diaphragm 22, can be assembled into a unitary form, according to the present invention, for insertion as a unit into the well point body, following which, the couplings 26, 26 are then screwed onto the tubes 24, 24 to seal the same in the upper diaphragm 20 which may have previously been welded to the upper end of the pipe 2. All parts of the well point are of sturdy and relatively simple form which materially contributes to a substantial reduction in manufacturing cost, while having little or nothing to get out of order.

While the specific details have been herein

shown and described, my invention is not confined thereto as changes and alterations may be made without departing from the spirit thereof as defined by the appended claims.

I claim:

1. In a well point, comprising an elongated tubular body having liquid inlet openings in the wall thereof at spaced intervals along its length, closure means at opposite ends of the body defining therebetween a float chamber within the body normally in communication with the exterior of the body through the inlet openings aforesaid, means forming at least one open-ended jetting-and-suction passage within the tubular body, said latter means being extended from one closure means aforesaid at the top of the tubular body to the other closure means at the bottom end, through the float chamber, to isolate the jetting-and-suction passage from the float chamber, the lower of said closure means having a passage therethrough for establishing and interrupting communication between the float chamber and the lower end of the jetting-and-suction passage, a jetting tip connected to the lower end of the tubular body and forming a continuation thereof, and check-valve means disposed within the jetting tip and operable to open position responsive to the passage of a jetting fluid downwardly through the jetting-and-suction passage, the combination of a valve for the passage through the lower closure means, said valve being positioned outside the float chamber and movable towards and away from the lower side of said closure means to respectively close and open the passage, said valve also being aided towards its passage closing position by the back pressure of the jetting fluid acting thereagainst, and a float in the float chamber operatively connected to the valve to close the same upon falling of the liquid level in the float chamber.
2. A well point as defined in claim 1, wherein the float is so constructed as to inherently have relatively little buoyancy, whereby to offer minimum resistance to movement of the float-operated valve in its movements towards and away from the closure means passage, with the dead-weight of the float acting to forcibly close the valve on falling of the liquid level in the float chamber.
3. A well point as defined in claim 1, wherein the jetting-and-suction passage forming means and the float each have the form of elongated tubes arranged in spaced parallel relation within the tubular body, with the float tube closed at its opposite ends and connected at its lower end to the float-operated valve.
4. In a well point, comprising a tubular body having screened liquid inlet openings in the wall thereof, a pair of diaphragms extending transversely across the interior of the tubular body in axially spaced relation to each other and defining a float chamber therebetween, a plurality of jetting-and-suction tubes extending axially through the float chamber between the diaphragms and opening into the tubular body aforesaid at their opposite ends above the upper diaphragm and below the lower diaphragm, respectively, said lower diaphragm having a passage therethrough for establishing and interrupting communication between the float chamber and the lower ends of the jetting-and-suction tubes, and a tubular jetting tip connected to the lower end of the tubular body and provided with check-valve means therein closing the jetting tip during the withdrawal of liquid from the soil

in which the well point is sunk, into the well point through the screened inlet openings in the tubular body, the combination of a valve for the passage through said lower diaphragm, said valve being below and movable towards and away from the diaphragm to respectively close and open the passage, and a float in the float chamber operatively connected to the valve to close the same upon falling of the liquid level in the chamber.

5. A well point as defined in claim 4, wherein the jetting-and-suction tubes are two in number arranged in spaced parallel relation to each other respectively on opposite sides of the central axis of the tubular body, and wherein the float comprises a pair of tubular members, closed at their opposite ends and connected together in spaced parallel relation to each other, with the tubular float members arranged parallel to the jetting-and-suction tubes and respectively disposed on opposite sides of a plane passing through the central axis of the jetting-and-suction tubes.

6. A well point as defined in claim 4, wherein the connection between the float and diaphragm passage controlling valve comprises a link pivotally connected at one end to the float and depending therefrom, a lever pivotally supported between its ends in the tubular body for rocking movements in opposite directions about an axis transversely related to the central axis of the tubular body, said lever being pivotally connected at one end to the lower end of the link aforesaid, and a valve rod pivotally connected at one end to the opposite end of the lever and extending through the passage in the lower diaphragm for connection at its other end to the valve.

7. A well point as defined in claim 4, wherein the connection between the float and diaphragm passage controlling valve comprises a link pivotally connected at one end to the float and depending therefrom, a lever pivotally supported between its ends in the tubular body for rocking movements in opposite directions about an axis transversely related to the central axis of the tubular body, said lever being located a substantial distance above the lower diaphragm and the valve-controlled passage therein and pivotally connected at one end to the lower end of the link aforesaid, and a valve rod pivotally connected at one end to the opposite end of the lever and extending through the passage in the lower diaphragm for connection at its other end to the valve.

8. A well point as defined in claim 4, wherein the valve-controlled passage through the diaphragm is located near the wall of the tubular body, and the valve coacting with said passage is slidably engageable with the wall of the tubular body so as to automatically align the valve with the passage in the diaphragm.

9. A well point as defined in claim 4, wherein the valve is hemispherical in shape and arranged with its spherical surface next to the diaphragm and adapted to seat in said passage on closing the valve.

10. A well point as defined in claim 4, wherein the connection between the float and diaphragm passage controlling valve comprises a link pivotally connected at one end to the float and depending therefrom, a lever pivotally supported between its ends in the tubular body for rocking movements in opposite directions about an axis transversely related to the central axis of the tubular body, said lever being pivotally connected at one end to the lower end of the link

aforesaid, and a valve rod pivotally connected at one end to the opposite end of the lever and extending downwardly therefrom at an inclination towards the central axis of the tubular body, through the passage in the lower diaphragm for connection at its other end to the valve.

11. A well point as defined in claim 4, wherein the jetting-and-suction tubes are extended through the upper and lower diaphragms and are connected thereto in fluid-tight sealed relation.

12. A well point as defined in claim 4, wherein the jetting-and-suction tubes are extended through the upper and lower diaphragms and are connected thereto in fluid-tight sealed relation; and the tubes being detachable from at least one of the diaphragms.

13. A well point as defined in claim 4, wherein the jetting-and-suction tubes are extended through the upper and lower diaphragms and are connected thereto in fluid-tight sealed relation, the connection with one of the diaphragms having the form of tubular coupling members having threaded engagement with the ends of the respective tubes and abutting the diaphragm in the manner of a hollow jamb-nut.

14. A well point as defined in claim 4, wherein the upper diaphragm is rigidly secured to the tubular body, and the lower diaphragm is seated on the lower end of the tubular body and releasably clamped between the same and the upper end of the jetting tip.

15. A well point as defined in claim 4, wherein the jetting-and-suction tubes, the float, the lower diaphragm, and the float-actuated valve, together have the form of a unitary assembly which is bodily insertible as a unit into the tubular body, and removable therefrom.

16. A well point as defined in claim 4, wherein the float is connected to the float-actuated valve by means including a lever fulcrumed between its opposite ends for rocking movements in opposite directions about a horizontal axis and supported by the jetting-and-suction tubes.

17. A well point as defined in claim 4, wherein the float is connected to the float-actuated valve by means including a lever fulcrumed between its opposite ends for rocking movements in opposite directions about a horizontal axis and attached to the jetting-and-suction tubes by a supporting plate arranged transversely within the tubular body and having portions of its marginal edges spaced from the surrounding wall of the tubular body.

18. In a well point, comprising a tubular body adapted to be sunk in fluid-containing soil for withdrawing the liquid therefrom, said tubular body having a plurality of screened liquid inlet openings in the wall thereof leading into a chamber which is closed at its upper end and provided with a port at its lower end, and a jetting-and-suction conduit extending axially through the tubular body from a point above said chamber to a point below the port at the bottom thereof,

whereby the flow of liquid in either direction through the jetting-and-suction conduit will be isolated from the chamber, the combination of single valve means for the port at the lower end of the chamber, said valve means being below the chamber and movable towards and away from the port to respectively close and open the port responsive to the fall and rise of the liquid level in said chamber, and said valve means being also automatically operable responsive to the passage of a jetting fluid through the jetting-

11

and-suction conduit to close the port at the bottom of the chamber and thereby prevent back waste of the jetting fluid into the chamber and outwardly through the liquid inlet openings.

19. In a well point, comprising a tubular body adapted to be sunk in fluid-containing soil for withdrawing the liquid therefrom, said tubular body having a plurality of liquid inlet openings in the wall thereof leading into a chamber which is closed at its upper end and provided with a port at its lower end, and means for selectively conveying jetting and suction fluids through the tubular body in isolated relation to the chamber aforesaid, the combination of a valve head, a valve seat, said valve head engaging the valve seat on upward movement of the valve head responsive to the liquid level in said chamber to prevent the entrance of air into the jetting and suction fluid conveying means and also operable responsive to the passage of a jetting fluid through the conveying means to prevent back waste of the jetting fluid into the chamber and out through the liquid inlet openings.

20. In a well point, comprising a tubular body adapted to be sunk in fluid-containing soil for withdrawing the liquid therefrom, said tubular body having a plurality of liquid inlet openings in the wall thereof leading into a chamber which is closed at its upper end and provided with a

12

port at its lower end, a plurality of jetting-and-suction tubes extending through the tubular body from a point above the chamber aforesaid to a point below the port at its lower end, a second chamber located below the first-mentioned chamber and normally in open communication with the lower ends of the jetting-and-suction tubes, and a check-valve arranged below the second chamber, the combination of a valve arranged in the second chamber and movable towards and away from the lower side of the port at the bottom of the first-mentioned chamber, and a float arranged in the first-mentioned chamber, said float being freely movable in its chamber responsive to the rise and fall of the liquid level therein, and being operatively connected to the valve in the second chamber through the port at the bottom of the first-mentioned chamber.
